UNITED STATES PATENT OFFICE

CARL E. CHRISTOPHEL, OF PEARL RIVER, NEW YORK, ASSIGNOR TO DEXTER FOLDER COMPANY, OF NEW YORK, N. Y., A CORPORATION OF NEW YORK

FOLDING MACHINE

Application filed October 2, 1925. Serial No. 60,108.

The present invention is an improvement in folding machines, and the particular object of the invention is to provide a universal folding machine on which, by a simple and ready adjustment, sheets of paper can be folded in any desired manner.

Heretofore commercial folding machines have been limited in their output with respect to the number of different folds that could be made thereon; and for this reason it has been necessary to manufacture a large number of different types of folders in order to meet the requirements of the trade for sheets folded in all of a large variety of styles.

By the present invention there is provided a single folder on which sheets can be folded in any of numerous varieties of ways; for example, parallel folds may be followed by right-angular folds, or vice versa, or the folds may be all right-angular folds or all parallel folds. In short, any combination of folds which have heretofore required a large number of special folding machines may be readily and satisfactorily performed on the present device.

The objects of the invention are secured, generally, by the provision of a plurality of folding tables adjustably mounted with respect to one another, with means for transmitting the sheets from one table to another until the final product having the desired number of folds is delivered from the machine.

Numerous features of invention will appear as the machine is described in detail.

The invention will be better understood by reference to the accompanying drawings, illustrating one expression of the inventive idea, and wherein—

Fig. 1 is a perspective view of the improved device, with the folding tables arranged at right angles to each other so that the final product with the machine so adjusted will have four right-angular folds;

Fig. 2 is a sectional elevation of the machine as shown in Fig. 1, the section being taken through the central standard;

Fig. 3 is a perspective view of the top folding table with associated mechanism for registering and folding the sheets;

Fig. 4 is a detail of one form of the sheet-registering device;

Fig. 5 is a side elevation of one of the folding tables with the supporting frame shown in section.

Fig. 6 is a perspective view of one of the foregoing blades and associated parts;

Fig. 7 is a perspective view of the mechanism for elevating and depressing the folding blades;

Fig. 8 is a side elevation, with various parts removed, showing the tables arranged in position to form four parallel folds in the sheets, and showing the sheet delivery mechanism between the several folding tables;

Figs. 9 and 10 are views similar to Fig. 8, with the sheet delivery means between the tables swung to different positions to give different types of parallel folds;

Fig. 11 is a perspective view of one of the castings which is mounted on the central column and to which a folding table is secured;

Fig. 12 is a perspective view of a second form of sheet-feeding or sheet-positioning device which operates to push rather than pull the sheet into engagement with the guides;

Figs. 13 and 14 are details of the same;

Fig. 15 is a section on the line 15—15 looking in the direction of the arrow;

Fig. 16 is a modified form of sheet delivery device between the tables;

Figs. 17 and 18 are details of the drive for the antifriction rollers carried by the tables and for the sheet-feeding or sheet-positioning device.

Referring to the accompanying drawings, wherein like reference numerals indicate like parts, 20 indicates a suitable base or support on which is mounted a column or standard 21 which is secured on said base 20 in any desirable manner as by bolts 22.

Mounted on the column 21 is a plurality of folding tables, here shown as four, and indicated generally by numerals 23, 24, 25 and 26. It will be understood that any desired number of folding tables may be employed, but four have been found to meet the reasonable and normal requirements.

Each of the tables is preferably secured

to a support or casting 27 (Fig. 11) which casting is rotatable with the table secured thereto into any desired position of adjustment about the column 21, and means are provided for securing the casting and its associated table in any desired position of adjustment. As here shown, lock screws 28 and 29 pass through lugs 30 and 30' integrally formed on said casting, and are tightened to hold the casting in the desired position on the column.

Each folding table is preferably provided with means for feeding or positioning the sheets with respect to the folding mechanism, here shown as a pair of folding rollers 31 and 32 and a folding blade 33 (Fig. 3), and each table has associated therewith sheet delivery means for conveying the sheets successively from one table to the next. The sheet conveying means for carrying the sheets from one table to another is preferably in the form of a plurality of sets of rollers 34, 35, 36 and 37; and as shown particularly in Figs. 8, 9 and 10, these sheet delivery means may be moved to different positions dependent upon the nature of the folds that it is desired to make and the relative positions of the several folding tables. Suitable registering mechanism is associated with the several tables in order to properly position the sheets with respect to the folding rollers; though it will be understood that for parallel folds the necessity for side register is removed.

After the tables are moved into the desired position of adjustment for effecting the desired fold, the folding blades 33 are preferably simultaneously operated. All of these folding blades and their associated actuating mechanism are preferably of the same construction. As here shown, each blade is elevated by a cam 38 keyed to a shaft 39 mounted in bearings in the base 20. This shaft carries a gear 40 which is driven by a pinion 41 mounted on the armature shaft of a motor 42. Cooperating with the face of the cam 38 is a roller 43 carried in the lower end of a rod 44 that extends through and is suitably spaced for movement in the hollow column 21. Bushings 45 and 46 are interposed between the column 21 and the rod 44. Disks 47 are carried by the rod 44, and are secured thereto in any suitable manner. One such disk is provided for each folding blade 33. As here shown, slots 48 and 49 are provided in the column 21 through which slots project brackets 50 and 51, which brackets are suitably secured to the rod 44. Each disk 47 is mounted on a pair of said brackets. The disks 47 participate in the upward and downward movement of the rod 44, and accordingly impart to the folding blades corresponding movements, through suitable connections. As here shown an adjusting screw 52 passes through the end of a casting 53 on

which the folding blade 33 is mounted, and this adjusting screw 52 engages the upper surface of the disk 47. It will therefore be seen that through these connections all of the folding blades are simultaneously elevated 70 and depressed so that the sheets, in their various conditions on the several tables, are simultaneously operated upon by the several folding blades.

Referring particularly to Figs. 1 and 6, 75 it will be noted that the folding blade 33 is mounted on a casting 54 through which casting a shaft 54' passes. This casting is provided with bearing surfaces 55 and 56, the former engaging in a guide bracket 57 mounted on the side of the table, and the latter in guide brackets 58 carried by plate 59 secured on the top of casting 27. These guide brackets 57 and 58 insure the accurate positioning of the folding blade in proper position above 85 the folding rollers 31 and 32.

In order to maintain the folding edge of the blade 33 in the same horizontal plane, means are provided for insuring that both extremities of the blade 33 shall be positively controlled in its movement. This is preferably effected by means of a pair of segments 60 and 61 secured in any suitable manner on the shaft 54', said segment 60 meshing with a stationary rack 62 mounted on the 90 side of the table, and a rack 63 (Fig. 3) mounted on the opposite side of the table. As the folding blade 33 is elevated and lowered, the engagement of segments 60 and 61 with their cooperating stationary racks will 100 prevent one end of the blade from getting out of alignment with the other end of the same for any reason.

The folding rollers 31 and 32 are preferably of the usual type, and are driven in opposite directions by means of meshing gears 64 and 65 (Fig. 3) carried by shafts 66 and 67 respectively. A gear 68 mounted on the opposite end of shaft 66 meshes with a gear 69 carried by shaft 70, the other end of which shaft carries bevel gear 71 that meshes with a similar bevel gear 72 carried on the upper end of a shaft 73 mounted in bearings 74 and 75 (Fig. 11) of casting 27. The lower end of shaft 73 carries a pinion 76 that meshes with gear teeth 77 formed on the same gear with gear teeth 78.

Each table is provided with means for feeding the sheets into position over the folding rollers and under the folding blade; and preferably two sets of such feeding means are employed, one on each side of the folding rollers, in order to provide for positioning the sheet in either direction on the table according to the nature of the fold to be made. As shown particularly in Figs. 3 and 4, each feeding means is in the form of a chain conveyor provided with sheet engaging means that operate to automatically close to seize the sheet and to automatically open when the 125

sheet is registered against the gauges. The conveyor is here shown in the form of a pair of sprocket chains 79 and 80, said chains carrying a cross rod 81, on which rod the sheet engaging member is carried. As shown in Fig. 3, two sheet-positioning grippers are employed although one may be used. As here shown, this sheet-positioning gripper is composed of an upper member 84 pivoted at 85 to a lower member 86. The upper member carries a roller 87 that is adapted to be engaged by a cam surface 88 provided on the end of an arm pivoted at 89, the other end of said arm having a socket 90 in which the rod 81 engages. The said arm is preferably formed in two parts 91 and 92 and these parts are secured together by means of a rod 93 which is screw-threaded into part 92 and passes through an opening in part 91, the parts 91 and 92 being held together and in intimate engagement with the cross rod 81 by means of spring 94. When it is desired to separate the parts 90 and 91 to place the arm on the opposite side of the table, the arm can be readily disengaged from the rod by means of the fingerhold 94' whereby the part 92 can be readily separated from the part 91.

The upper jaw 84 is normally held in its closed position as shown in Fig. 4 by means of a spring 95 carried by a pin 96. Any desired adjustment of said spring, one end of which bears against the lower face of jaw 86, may be had by means of adjusting-nut 97.

The upper surface of each folding table is provided on each end thereof with a plurality of slots 98, these slots being positioned for proper spacing of the grippers, to accommodate sheets of any desired size, the slots 98 receiving the lower member 86 of the sheet-positioning gripper. The slots extend to the ends of the table so as to permit ready engagement and disengagement of the grippers.

The conveyor chains 79 and 80 at the left-hand side of the machine as seen in Fig. 3 are driven from gear 69 which meshes with a gear 99 carried on shaft 100. Shaft 100 carries a gear 100' that meshes with pinion 101 on shaft 102, the latter carrying sprocket wheel 103 around which the chain 80 passes. The sprocket chain 80 passes around sprocket wheel 105 on stud 105'. On the other end of shaft 100 is carried a gear 99' corresponding to gear 100', which gear 99' meshes with a gear 101' mounted on a shaft 102' which also carries a sprocket 103' around which passes the sprocket chain 79. Said chain passes around a sprocket 106 mounted on a stud 106'.

The drive of the sheet-conveying mechanism on the right-hand side of the table as seen in Fig. 3 is effected through gear 107 mounted on shaft 108 carrying bevel gear 109 that meshes with bevel gear 110 on shaft 111. This shaft 111 carries a pinion 112 that meshes with gear teeth 77. Gear 107 meshes

with a gear 113 mounted on a shaft 113' extending across the table and carrying a gear 99" which meshes with a gear 101" mounted on a shaft 102" carrying a sprocket 103" that drives the chain 79' on the right-hand end of the table. Shaft 113' carries a gear 113" that meshes with a pinion 101' carried by shaft 102' on which is mounted sprocket 103' around which the sprocket chain 80' on the right-hand side of the table passes. In other words, as here shown, the driving connections on the two ends of the table are preferably the same.

It will be understood that, in the position of the parts as shown in Fig. 3, the sheets will be fed from a pile 118 automatically or manually into position to be engaged by the sheet-positioning gripper or grippers 84. The gripper jaws 84 and 86 will close on the sheet, and as the sheet is moved in the direction of the arrow 119 (Fig. 3) the forward or advancing edge of the same engages the gauge 120 (shown in dotted line in Fig. 3), which gauge is carried by rods 121 and 122 mounted in brackets 123 on the table. No side registering gauge is provided on the first or top-most table, though one could be provided if desired. The sheet having been properly positioned over the folding rollers 31 and 32, the folding blade 33 descends and the folded sheet passes downwardly on the sheet-delivering mechanism 34 into position on the next folding table 24. This sheet delivery mechanism is the same between the several tables. It preferably consists of a plurality of series of rolls 124 (Figs. 2, 8 and 16) mounted on shafts 125 carried in arms 126 and 127. These arms are pivoted on a shaft 128 which preferably carries a guide or deflecting plate 129 that projects rearwardly to guide the sheet from the folding rollers 31 and 32 onto rollers 124. The shafts 125 are preferably driven by sprocket chains 124' engaging sprockets 125' carried by shafts 125, from shaft 128 that carries on one end thereof a gear 130 (Fig. 16). This gear 130 meshes with a gear 131 that is mounted on a stud 132 carried by a swinging arm 133 pivoted on shaft 128. This gear 131, as shown in Fig. 8, is in mesh with gear 65 on shaft 67. If, however, the sheet delivery mechanism 34 is swung from the position shown in Fig. 8 to that shown in Fig. 10, the gear 131 is then meshed with gear 64. The swinging arm 133 is secured in any desired position of adjustment by the pin and slot connection 134, it being understood that the sheet delivery means are to be held securely in any desired adjusting position.

Referring to Fig. 1, as the folded edge of the sheet passes downwardly from the sheet delivery mechanism 34 onto the table 24, it engages the gauge 135 mounted on rods 136 and 137, said gauge 135 extending lengthwise of the table 24 and being adjustable along the

rods 136 and 137 to compensate for sheets of varying size. Thereupon the sheet-positioning gripper 84' will seize the sheet and position it beneath the folding blade 33', the sheet being brought by the sheet-positioning gripper 84' into engagement with the gauge 138 which is adjustable lengthwise of the table 24 in one of the slots 98.

From the table 24 the sheet, provided with two folds, at right angles to each other, is delivered to table 25 by means of the sheet delivery mechanism 35. The advancing folded edge of the sheet engaging the gauge 139 mounted on rods 140, 141, and the sheet-positioning gripper moves the folded sheet parallel with the gauge 139 until the sheet engages the gauge 142, and is properly positioned beneath the folding blade 33'. Thereupon the folded sheet, provided with three folds at right angles to each other, is fed downwardly on the table 26 where it receives its fourth fold, and is thereupon delivered to any suitable delivery mechanism. Such a delivery mechanism has been conventionally shown as an endless belt 143 (Figs. 1 and 8) which may be moved in any suitable manner as by the usual ratchet mechanism. A stop 144 (Fig. 8) is indicated as being associated with said belt 143, the delivered sheets engaging said stop as they pass onto the belt 143.

Power is transmitted to the various movable parts associated with each of the tables in such a manner that the driving connections are unaffected by the relative adjustment of the tables. Power will be transmitted just as efficiently if the machine is making all of the folds parallel, all of the folds at right angles to each other, or any combination of folds. This is effected generally by a planetary arrangement of the power transmitting elements.

As shown particularly in Fig. 2, the folding rolls and the sheet-positioning mechanism and the sheet delivery mechanism are driven from shaft 39 (Figs. 1 and 2) through bevel gears 145 and 146, the latter being mounted on a shaft 147 that carries at its upper end a gear 148 meshing with gear teeth 78' on the double gear which is also provided with gear teeth 77', which latter mesh with and drive a gear 149 carried by a shaft 150 that also carries a bevel gear 151 meshing with a bevel gear 152 which bevel gear 152 corresponds to bevel gear 71 or 109 (Fig. 3). On the upper end of shaft 150 (Fig. 2) is mounted a pinion 153'' that meshes with the gear teeth 154 on the lower half of a double gear 155, the upper half of which carries gear teeth 155' that mesh with a gear 156 on shaft 157. From this shaft 157 power is transferred to the mechanism associated with table 25, through bevel gear 158. The upper end of shaft 157 carries a pinion 159 that meshes with the gear teeth

on the lower half of a double gear 160, the teeth on the upper half of said gear meshing with a pinion on the lower end of a shaft 161 which shaft 161 drives the mechanism associated with the table 24. The upper end of the shaft 161 carries a pinion 162 that meshes with gear teeth 78 on the uppermost double gear, and thus drives the mechanism associated with the uppermost table 23 as heretofore described. 70

It will be understood that the drive as shown on Fig. 3, through shafts 73 and 111, to the mechanism on both ends of the feed table, is duplicated in connection with the other tables 24, 25 and 26; for example, there are two shafts 161, two shafts 157 and two shafts 150, each pair of these shafts corresponding to shafts 73 and 111. 75

As heretofore stated, the several tables 23, 24, 25 and 26 are each secured in any suitable manner, as by bolting or otherwise to its respective support or casting 27; and four such castings in the device as illustrated herein are shown on Fig. 2. These castings are spaced along the hollow column 21 by means of 85 bronze or other suitable bushings, which bushings are somewhat wider than the double gear with which they are associated. Preferably, these bushings have a driving fit with the column 21 and they act to space the castings 90 27 from each other as clearly illustrated. These bushings are also utilized as bearings for the double gears. In assembling the device, it will be understood that the lowermost bronze bushing 163' is first placed about the 100 column (being preferably pinned thereto) and that thereupon the lowermost double gear is then positioned about the bushing, one face of the gear resting on the flange 21' of the column 21. Thereupon the lowermost 105 casting 27' is slipped over the column 21 and rests on the top of the bronze bushings 163', leaving a slight clearance between said castings and the double gear that rests on the flange 21'. Thereafter the second bronze 110 bushing 163'' is positioned on the column 21 in engagement with the casting 27', this second bushing supporting the casting 27'' in the same manner; and so on until the complete number of bushings, double gears and 115 castings have been assembled on the column 21, the whole being held in place by the cap plate 21'. 120

In order that the sheets may be readily fed into position, with respect to the folding knives and rollers on the several tables, I prefer to mount on each end of each table a set of rollers 170 (Fig. 3). Each roller is mounted on a shaft 171 having suitable bearings in the table, and the rollers are arranged to project slightly above the surface of the table. The rollers of each set are preferably driven positively and in the same direction. To this end each shaft 171 carries a sprocket 172 around which passes a sprocket chain 173, 130

said chain also passing around idlers 174. The sprocket chain 173 also passes around and is driven by a sprocket 175 mounted on one end of a shaft 176, carried in suitable bearings on the side of the table. A bevel gear 177 keyed to the other end of shaft 176 meshes with a bevel gear 178 compounded with gear 99 which is loosely mounted on shaft 100 (Figs. 17 and 18). Accordingly, when gear 99 rotates, the rollers 170 will be driven.

In order to adjust the position of grippers 84 for different sizes of sheets, and in order to disconnect the grippers 84 on one end of the table when those on the other are in operation, a clutch is provided between the shaft 100 and the gear 99 which, as above noted, is loosely mounted on the right-hand end of shaft 100. Shaft 100 is only driven through gears 69 and 99 when the clutch is closed. As shown in Figs. 17 and 18, clutch teeth 180 on gear 99 are adapted to be engaged by clutch teeth 181 on the collar 182 which is pinned to shaft 100. In Figs. 17 and 18, the clutch is shown disengaged, this being effected by a longitudinal movement of the shaft 100 from the dotted line position to the full line position (Fig. 17). The shaft 100 will be driven through gear 99 when it has been returned to the dotted line position of the knob 183, thus engaging the clutch teeth 180 and 181. The gears 99' and 100' are secured to the shaft 100 by slot and key connections 184 and 185 (Fig. 18) which permit the longitudinal displacement of the shaft 100 without disturbing the connection between the shaft 100 and said gears. Stops 186 and 187, secured to the frame of the machine, prevent longitudinal displacement of gears 99' and 100'.

When the clutch is disengaged, the sprocket chains 79 and 80 will not be driven. At this time any desired adjustment of the position of the grippers 84 can be effected simply by turning the shaft 100 manually through the knob 183, and then closing the clutch; or, the clutch being opened, the drive to the sprocket chains 79 and 80 will be broken, though, as shown, the rollers 170 will continue to be rotated through the connections described.

As heretofore described, the grippers 84 on each of the tables operate to seize the sheet and pull it into engagement with the gauges. I preferably, however, provide means at the third and fourth fold mechanism on tables 25 and 26 for pushing the sheet into engagement with the gauges. A preferred form of such a pusher device is shown in Figs. 12, 13, 14 and 15, in which 190 is a carriage that slides in one of the slots 98 and is secured to cross rod 81. A pusher 191 is mounted on said carriage and moves therewith. It carries a lug 192 that engages the edge of the sheet to push the same. Suitable connections are provided between the rod 81, the carriage 190

and the pusher 191 so that the latter will rise to engage and push the sheet and will then be lowered and returned to position to engage the next sheet. This movement is effected by means of arms 193 and 194, connected to a U-shaped member 194' that engages the rod 81 and is removably held in place thereon by a plate 195 pivoted at 196 to arm 194 and held in the position shown in Fig. 12 by spring 197. The pusher can be readily removed from the rod 81 by moving the plate 195 away from the member 194' against the tension of the spring. Arm 193 is pivotally connected at 198 to the U-shaped member. The other end of said arm is bifurcated and is provided with alined openings 199 and 200. A pin 201 that acts as a fulcrum passes through openings 199, through alined elongated slots 202 in the carriage 190 and through a slot 203 in the pusher 191. A second pin 204 passes through the openings 200 and slot 203, but not through any openings in the carriage 190. The free end of arm 194 is perforated, the perforation being alined with openings 205 in the carriage 190. A pin 206 passes through the alined openings 205, the perforation in the arm 194, and also through an opening in one end of a pair of short horizontal links 207 and 207', the other end of which links is carried by a pin 208 that passes through a perforation 209 in a lug 210 on said pusher 191. It will be observed that the carriage 190 and the pusher 191 participate in the movements of the cross rod 81 and that, through the connections described between the rod 81, the carriage 190 and the pusher 191, the latter will be elevated to engage the edge of the sheet and push it forward into engagement with the gauge, and then depressed after its pushing action is completed.

It is pointed out that, by the use of the device of the present invention, any known fold can be made that is made on any of the machines now in commercial use. In this connection it is to be understood that more or less than four tables may be had. If the tables are arranged as illustrated in Fig. 1, the sheet will be folded with four right angular "over and over" folds or what is known as book folding. On the other hand, if the table 25 should be swung around so that it is positioned under table 23 and parallel thereto the sheet would still receive four folds at right angles to each other, but the sheet would be turned over after receiving the second fold, thus giving what is known as a "newspaper" fold. In that event the sheet, instead of being delivered toward the right as shown in Fig. 1, would be delivered toward the left onto table 25 as shown in that figure; in other words, the sheet delivery mechanism 35 would be swung out of the position shown in Fig. 1 to a position to deliver the sheet onto the table 25 in its new position.

If tables 23, 24 and 25 were left in the po-

sition shown in Fig. 1 and table 26 was swung beneath and parallel to table 25, there would thus be secured a folded sheet with three 5 folds at right angles to each other and the fourth fold parallel with the third. This is known as "parallel 32 2 up work." If table 25 were swung from the position shown in Fig. 1 under and parallel to table 24, and the use of table 26 discontinued, the resulting 10 work would be what is known as "2 right angles followed by 1 parallel" or "parallel 16 2 up work." If table 24 should be swung around under and parallel to table 23 and table 25 should be swung around at right 15 angles to the position illustrated in Fig. 1, and the use of the table 26 discontinued the work produced would be known as "two-fold parallel followed by one right angle" or "oblong" or "catalog" folding.

20 If the tables and the sheet-feeding mechanisms are arranged as shown in Fig. 8, the sheet would be provided with four parallel folds, every other fold of which would be a "turnover" fold. With this same arrangement of the feed tables and the sheet-conveying mechanism, if the sheet were folded one quarter off at the first fold and one quarter off at each succeeding fold, the work produced would be what is known as "accordion" 25 folds. If the tables were arranged parallel with the feeding devices between the tables also parallel, the work produced would be known as "straight over and over parallel" 30 folds (Fig. 9).

35 As shown in Fig. 1, it is noted that the sheet in the process of folding is progressed in an anti-clockwise direction around and through the folder. It will be readily appreciated that the tables can be positioned so that the sheets are fed around and through 40 the machine in a clockwise direction. This would give a different arrangement of the make-up of the folded product.

The foregoing are only a few illustrations 45 of the many folds that can be made on this device. Dependent upon the position of the gauges and of the sheet delivery mechanisms between the tables and the location of the particular sheet-positioning gripper that is used 50 on each table, the device is adapted to make any combination of folds that may be desired.

55 It will be understood that after the machine has been adjusted for the particular type of fold to be made, the first sheet will be fed downwardly between the uppermost set of folding rollers 31 and 32 by the folding blade 33, the other three folding blades at this time performing an idle movement. 60 When the first sheet is positioned beneath the second folding blade, another sheet will have been fed to the first folding blade, and when the first sheet is under the third folding blade a sheet will be under the second and first folding 65 blades and so on until all of the folding

blades are simultaneously operating on sheets in different stages of folding.

70 While for the purpose of illustration one expression of the inventive idea has been herein shown and described in detail, it is to be understood that the invention is susceptible of various mechanical expressions within the limits of the appended claims.

What is claimed is:—

1. In a folding machine, the combination 75 of a plurality of tables arranged one above the other, means for positioning said tables angularly with respect to one another, folding means carried by said tables, delivery means between said tables, and means for changing the direction of said delivery means.

2. In a folding machine, the combination 80 of a plurality of tables arranged one above the other, means for positioning said tables angularly with respect to one another, folding means carried by said tables, delivery means between said tables, and means for 85 swinging said delivery means to change the direction of delivery of the sheets.

90 3. In a folding machine, the combination 95 of a plurality of tables arranged one above the other, means for positioning said tables angularly with respect to one another, folding means carried by said tables, delivery mechanism pivoted to the underside of each table, and means for changing the direction of delivery of the sheets.

4. In a folding machine, the combination 100 of a plurality of tables arranged one above the other, means for positioning said tables angularly with respect to one another, folding means carried by said tables, delivery mechanism pivoted to the underside of each 105 table, and a deflector associated with the folding and delivering means.

5. In a folding machine, a plurality of superposed folding tables, a central standard 110 on which said tables are mounted and about which they are movable, a folding blade associated with each table and a common actuating element carried by said standard for simultaneously raising and lowering said folding blades.

115 6. In a folding machine, a plurality of superposed folding tables, a central column on which said tables are mounted and about which they are adjustable, a folding blade associated with each table, and a common actuating element associated with said column for simultaneously raising and lowering said folding blades in all angular positions of adjustment of the same.

120 7. In a folding machine, a pair of folding rollers, a folding blade, means for raising and lowering said blade, means for guiding said blade in its movement, and a gear connection at each end of the knife for maintaining its folding edge in a horizontal position.

125 8. In a folding machine, the combination 130

of a column, a plurality of supports mounted on said column, spacing bushings interposed between said supports, a table mounted on each of said supports, and folding mechanism carried by each table.

5 9. In a folding machine, the combination of a column, a plurality of castings mounted on said column, spacing bushings interposed between said castings, a folding table mounted on each of said castings, folding rollers and sheet-positioning means carried by each table, and a driving gear for each table engaging one of said bushings.

10 10. In a folding machine, the combination of a plurality of folding tables, folding rollers carried by said tables, sheet-positioning means mounted on each side of the folding rollers on said tables, means for driving the folding rollers and one set of sheet positioning means, and independent means for driving the other set of sheet-positioning means.

15 11. In a folding machine, the combination of a plurality of folding tables, folding means and sheet-positioning means carried by each table, means for driving said folding rollers and sheet-positioning means, and means for changing the angular relationship of said tables without breaking the driving connection.

20 12. In a folding machine, the combination of a plurality of folding tables, folding means and sheet-positioning means carried by each table, a plurality of driving gears arranged one above the other, means for transmitting power from one to the other and to said folding means and sheet-positioning means, and means for changing the angular relationship of said tables without breaking said power connections.

25 13. In a folding machine, the combination of a plurality of tables adapted to receive sheets in successive stages of folding, means for adjusting said tables angularly with respect to each other, folding mechanism associated with each table, and common means for actuating said folding mechanism.

30 14. In a folding machine, the combination of a plurality of tables adapted to receive sheets in successive stages of folding, means for adjusting said tables angularly with respect to each other, folding mechanism associated with each table, and common means for simultaneously actuating said folding mechanism.

35 15. In a folding machine, the combination of a plurality of tables adapted to receive sheets in successive stages of folding, driving mechanism, means for adjusting said tables angularly with respect to each other about said driving mechanism, a folding knife associated with each table, and continuously maintained driving connections between the driving mechanism and the folding knives for simultaneously moving said knives to operate on a series of sheets in different stages 40 of folding.

16. In a folding machine, the combination of a plurality of folding mechanisms each including a folding blade and folding rollers arranged in parallel planes, driving means, means for relatively adjusting said mechanisms about said driving means in said planes, and continuously maintained driving connections between the driving means and said blades and rollers for simultaneously operating said blades and rollers in any adjusted position.

70 17. In a folding machine, the combination of a plurality of folding mechanisms arranged in parallel planes, means for adjusting said mechanisms with respect to each other in said planes, and planetary driving connections for operating said mechanisms in any adjusted position.

75 18. In a folding machine, the combination of a plurality of folding mechanisms each including a folding blade and folding rollers arranged in parallel planes, means for adjusting said mechanisms with respect to each other in said planes, and planetary driving means for operating said blades and rollers in any adjusted position.

80 19. In a folding machine, the combination of a plurality of folding mechanisms arranged in parallel planes, means for operating said mechanisms, and means for adjusting said mechanisms with respect to each other in said planes without breaking the operating connections.

85 20. In a folding machine, a table, folding mechanism arranged thereon, sheet-positioning means carried by endless conveying means arranged on each side of said folding mechanism, and means for delivering the folded sheet from the under side of said table.

90 21. In a folding machine, a table, folding mechanism carried thereby, sheet-positioning means associated with said folding mechanism, a shaft, a driving gear loosely mounted thereon, and a clutch between said gear and shaft.

95 22. In a folding machine, a table, folding mechanism carried thereby, sheet-positioning means associated with said folding mechanism, a shaft, a driving gear loosely mounted thereon, a clutch between said gear and shaft, and means for longitudinally moving said shaft to open said clutch.

100 23. In a folding machine, a pair of tables, folding mechanism carried by one of said tables, and means for delivering the folded sheet to the other table comprising a conveyor secured to the underside of said first table and movable to different angular positions.

105 24. In a folding machine, a pair of tables, folding mechanism carried by one of said tables, and means for delivering the folded sheet to the other table comprising a frame pivoted to said first table and a plurality 110

of positively driven rollers mounted in said frame.

25. In a folding machine, a table, folding mechanism carried thereby, means for positioning the sheet with respect to said mechanism including a carriage, a pusher mounted thereon, and means for reciprocating said carriage and pusher and elevating and depressing the latter.

10 26. In a folding machine, a table, folding mechanism arranged on the table between opposite extremities thereof, means for selectively moving sheets in opposite directions past the folding mechanism to position the sheets with respect thereto, and means for delivering the folded sheets from the under side of said table.

20 27. In a folding machine, a table, folding mechanism arranged on the table between opposite extremities thereof, means for selectively moving sheets in opposite directions past the folding mechanism to position the sheets transversely thereof, and two sets of positively driven rollers extending at right angles to the folding mechanism on opposite sides thereof respectively and adapted to position the sheets longitudinally of said folding mechanism.

25 28. In a folding machine, a table, folding mechanism arranged on the table between opposite extremities thereof, and means for selectively moving sheets in opposite directions past the folding mechanism to position the sheets with respect thereto.

30 29. In a folding machine, a table, folding mechanism arranged on the table between opposite extremities thereof, means for selectively moving sheets in opposite directions past the folding mechanism to position the sheets transversely thereof, and means for positioning the sheet longitudinally of said folding mechanism.

In testimony whereof I have signed this specification.

45 CARL E. CHRISTOPHEL.
